UNITED STATES PATENT OFFICE

113,856

DESIGN FOR A SERVING PLATTER OR SIMILAR ARTICLE

Claire K. Smith, Brooklyn, N. Y.

Application December 31, 1938, Serial No. 82,108

Term of patent 7 years

To all whom it may concern:

Be it known that Claire K. Smith, a citizen of the United States, residing in the Borough of Brooklyn, county of Kings, and State of New York, has invented a new, original, and ornamental Design for a Serving Platter or Similar Article, of which the following is a specification, reference being had to the accompanying drawing, forming a part thereof.

In the drawing:

Fig. 1 is a top plan view of a serving platter or similar article, showing my design;

Fig. 2 is a sectional view, taken on line 2—2 of Fig. 1; and

Fig. 3 is a sectional view, taken on line 3—3 of Fig. 1.

I claim:

The ornamental design for a serving platter or similar article, as shown.

CLAIRES K. SMITH.
